UNITED STATES PATENT OFFICE.

TIMOTHY FRANCIS CROWLEY, OF NEW YORK, N. Y.

CUTTER-GAGE FOR ICE-CREAM, &c.

SPECIFICATION forming part of Letters Patent No. 645,503, dated March 13, 1900.

Application filed May 11, 1899. Serial No. 716,338. (No model.)

To all whom it may concern:

Be it known that I, TIMOTHY FRANCIS CROWLEY, a citizen of the United States, residing at New York, in the county of Kings 5 and State of New York, have invented certain new and useful Improvements in Cutters for Ice-Cream and Similar Material, of which the following is a full and complete specification, such as will enable those skilled in the 10 art to which it appertains to make and use the same.

This invention relates to cutters for ice-cream and similar substances; and the object thereof is to provide an implement of this 15 class whereby blocks of ice-cream and similar material may be readily divided into slices, slabs, or cakes of any desired or predetermined bulk.

My invention is fully disclosed in the following specification, of which the accompanying drawings form a part, in which like reference characters denote like parts in the several views, and in which—

Figure 1 is a side elevation of an implement 25 constructed according to my invention; Fig. 2, a top view thereof, and Fig. 3 an end view thereof looking in the direction of the arrow.

Referring more particularly to the drawings, I provide a knife-blade *a* of any desired 30 form, but preferably of the form shown in Fig. 1, which corresponds to the cross-section of an ordinary block of ice-cream. To one end of the blade *a* I secure a handle *b*, as at *c*, and to the top thereof, approximately at the 35 opposite end, I secure a handle *d* by means of a yoke-shaped clamp *e*. Adjacent the handle *b* and to the top of the blade *a* I fix a standard *f*, provided with a sleeve *g*, in which is 40 slidably and horizontally mounted a rod *h*, which projects at right angles to the blade *a* and is provided upon its upper side with a scale *j*, which may be read in connection with the collar *g* to determine the extent of its 45 projection from said collar. A supplemental rod *k* is passed slidably and vertically through the outer end of the rod *h* and is provided at its lower end with a marker *l*, consisting of a thin, preferably metallic, strip. Thumbscrews *m* and *n* are operatively mounted, 50 respectively, in the collar *g* and rod *h* and operate, respectively, in connection with the rod *h* and supplemental rod *k*.

The operation of my improved implement will be evident from the foregoing description when taken in connection with the accompanying drawings and the following statement thereof.

The rod *h* is adjusted through the collar *g* until the supplemental rod *k* and marker *l* are at such a distance from the blade *a* as 55 shall correspond to the thickness it is desired the cakes to be cut shall have. The binding-screw *m* is then tightened down and the supplemental rod *k* is vertically adjusted to so 60 position the marker *l* that when the blade *a* has passed through the block of material to be cut it shall slightly impress the surface of 65 said block and mark the section-line at which the next slice is to be severed.

The scale *j* has its zero-marks adjacent the 70 supplemental rod *k*, and the exact distance between the collar *g* and supplemental rod *k* or, with the scale arranged accordingly, and the exact distance between the marks *l* and blade *a* may be readily determined, and the 75 marker "set" accordingly.

My invention is simple in construction and well adapted to accomplish the object in view, and the construction and adaptation thereof may be substantially varied without depart- 80 ing from the scope thereof.

Having fully described my invention, I claim as new and desire to secure by Letters Patent—

The herein-described instrument, comprising 85 a knife-blade provided at either end with a handle, an upwardly-directed standard connected with the upper edge of said knife-blade, a laterally-directed graduated rod adjustably connected therewith, a downwardly- 90 directed supplemental rod adjustably connected with said rod and provided at one end with a marker, and independent devices for securing said rod and supplemental rod in 95 adjusted position, substantially as shown and described.

In testimony that I claim the foregoing as my invention I have signed my name, in presence of the subscribing witnesses, this 10th day of May, 1899.

TIMOTHY FRANCIS CROWLEY.

Witnesses:
